(57) **CLAIM**

The ornamental design for a collapsible frame stock, as shown and described.

DESCRIPTION

FIG. 1 is a right-front perspective view of a collapsible frame stock showing our new design.

FIG. 2 is a right-rear perspective view thereof.

FIG. 3 is a left side elevation view thereof.

FIG. 4 is a right side elevation view thereof.

FIG. 5 is a top elevation view thereof.

FIG. 6 is a bottom elevation view thereof.

FIG. 7 is a front plan view thereof; and,

FIG. 8 is a rear plan view thereof.

The broken lines in the drawings disclose unclaimed portions of the collapsible frame stock only and form no part of the claimed design.
